UNITED STATES PATENT OFFICE

SAMUEL N. SAGER, OF CHICAGO, ILLINOIS

PULL-OFF LEGGING

Application filed November 5, 1928. Serial No. 317,173.

This invention relates in general to a quickly detachable legging which is removable by a single movement and is particularly adapted for use by workmen in foundries, machine shops and the like where sparks and molten particles are likely to strike them.

One of the principal objects of the invention is in the provision of a pull-off legging which has a quick detachable connection both 10 at the bottom and at the top with means at both ends for varying the size of the legging.

A further object of the invention is in the provision of a braced legging which fits down closely and tightly over the legs and shoes of 15 a wearer.

Other objects will appear hereinafter, the drawings illustrating a preferred form of the legging with modifications of the fastening means.

In the drawing, Fig. 1 is a side elevation of 20 a legging embodying the invention in a closed form; Fig. 2 is a view of the outer face of the legging in its open form; Figs. 3 and 4 are face and side views respectively of one form 25 of fastening device; Figs. 5 and 6 are face and side views respectively of modified brace and connector; and Fig. 7 is a detail perspective of a legging brace and connector as applied to the overlapping edge of a legging.

If leggings used by molders and other workmen do not fit properly, they are apt to 30 catch sparks or burning particles which lodge in openings or folds of the legging where they may burn through the legging and through 35 the clothes, severely burning the wearer. The present invention provides a quickly detachable legging which is braced at the sides to fit down tightly over the instep and shoes of the wearer with fastening means at top and 40 bottom which may be disengaged by a single jerking movement or pull at the top of the legging.

Referring more particularly to the drawing, the body of the legging consists of a single piece 10 of material such as leather having

a recess 11 at one side of the lower edge to fit over the instep and a yamp 12 secured to the edge of the recess by stitching or wire staples 13. The interior of the front of the legging is provided above the recess 11 with a protector and stiffener secured to the body of the legging by stitching 14 which extends through the canvas lining at the back of the legging, enclosing the stiffener.

The upper edge of the legging has a number of cuts 15 which are overlapped and secured together by wire staples 16 or other fastening means to make the legging fit tightly about the leg, preventing sparks or molten particles from lodging in the legging from 50 the top thereof.

The overlapping end of the body 10 is turned upon and stitched to itself to form a hem or recess 17 for receiving stiffening and fastening means for this end of the legging. 55 This hem is located at the outer side of the leg, the stiffening means being attached to the legging by a rivet or other fastening device 18 at one end of the recess 12 and at the other side of the leg is a stiffening bar 19 attached to the legging by rivets 20, the lower extremities of the stiffening members being formed with an offset 21 adjacent the lower ends thereof which will fit over and extend along the outsides of the shoes of a wearer.

The stiffening and fastening means for the overlapping end of the legging member consist of a single bar 22, as shown in Figs. 3 and 4 with a slot 23 forming extremities 24 and 25 bent oppositely, as shown in Fig. 4, so that one projects outwardly beyond the other, the other end being attached by means of a perforation 26 to the body of the legging; or a bar 27 may be cut at one end to provide an extension 28 offset from the body of the bar and with a straight piece 29 riveted to the body of the bar and extending at the side of the other extremity 28; or a pair of bars 30 and 31 may be inserted in the hem 17 side by side, one secured to the body of the legging by fastening 50 55 60 65 70 75 80 85 90 95

rings 18 at the bottom and upwardly in the legging, this bar having an offset 21 adjacent its lower end and forming a stay similar to the stay 19. The other bar 31 is secured to the body of the legging by a rivet 32 a short distance from the lower end of the bar so that the lower extremity 33 will be free from engagement with the adjacent portion of the legging.

10 To expose the lower end 33 of the bar, the hem 17 may be terminated just below the rivet 32, and a notch 34 omitted from this corner of the legging so that the extremity 33 of the bar may be easily inserted in any one of a number of pockets formed by a strip 34 attached to the body member at intervals by rivets 35 and providing means for adjusting the size of the legging at the bottom.

15 At the top of the legging is a plate 36 of metal or other suitable material having a number of spaced openings 37 for the engagement of a hook 38 attached through both sides of the hem and extending through the upper end of bar 31. This hook 38 has a flexible piece 39 of leather or other material projecting from it and adapted to be quickly grasped for pulling the hook from engagement with any one of the openings 37 of the plate 36.

20 The top of the underlying portion of the legging is provided with a projecting tab 40 which is easily grasped and held by one hand of a wearer in applying the overlapping portion to the leg.

25 With these stiffening and attaching bars the legging is extended and held in form-fitting relation to the leg and down over the instep so that sparks or molten particles are not likely to lodge in the shoe of a wearer.

30 The lower extremity of the fastening bar being exposed, supported and spaced from the adjacent end of the stiffening bar, is easily engaged with any of the lower attachment pockets. The lower end of the fastening bar

35 is entirely clear of all obstruction so that it will slip easily into and out of the attachment pockets, permitting and insuring that the legging may be easily disengaged when the top fastening means is disconnected so that only 50 a single motion is necessary for the complete removal of the legging.

I claim:

1. A quick detachable legging of the overlapping type having a pocket in the underlying portion, and means at the edge of the overlapping portion comprising two extremities extending to the bottom of the legging one attached to the body of the legging at the bottom thereof and the other free from attachment to the legging at its extremity and exposed for engagement in the pocket.

2. A quick detachable legging having a body portion adapted to be wrapped in overlapping relation about the leg of a user, means forming a plurality of pockets at the bottom

of the underlying portion, stiffening and attaching means in the overlying edge comprising two extremities of substantially equal length one attached at its end to the lower edge of the legging and the other being exposed and free from engagement with the legging at its lower end and adapted to engage for varying the size of the legging in any one of the pockets.

3. A quick detachable legging having a body portion with an overlapping edge fitting about the leg of a wearer terminating at the outer side of the leg, means forming vertical stays at the inner and outer sides of the leg and an unobstructed projection of the stay at the outer side of the leg only extending to the bottom of the legging, the underlying portion of the legging having pockets and the projection being adapted to engage in any one of the pockets.

4. A quick detachable overlapping legging having pockets at the lower edge of the underlying portion and bracing and fastening means in the overlapping edge comprising means extending from the top to the bottom at the edge of the legging and secured thereto but divided at the bottom so that one extremity is exposed and uncovered and spaced from the body of the legging and engageable in any one of the pockets.

5. A quick detachable pull-off legging having means forming pockets in the lower edge of the underlying portion, and stiffening and fastening means at the overlapping edge comprising two extremities, one secured to the body of the legging at the bottom, and the other free from such attachment and engageable in any one of the pockets, the legging being cut away to expose the unattached extremity for freely inserting it in any one of the pockets.

6. A quick detachable legging of the overlapping type having means forming a plurality of pockets in the underlying lower edge, stiffening and fastening means at the overlapping edge of the legging comprising two extremities spaced apart and offset with respect to each other, one of the extremities being secured to the lower edge of the body of the legging and the other extremity being free from engagement with the legging at its end, the legging being cut away to expose and free the unattached extremity from obstruction whereby it may be inserted and removed from the pockets, and quick detachable means at the top of the legging for withdrawing the extremity from the engaged pocket by the same movement which disengages the top fastening means.

7. A quick detachable legging of the overlapping type comprising a body member having means forming pockets at the bottom of the underlying portion, a plate having adjusting perforations at the upper part of the underlying portion, means forming braces

with offsets adjacent the bottom on opposite sides of the legging when applied to the leg of a wearer, the offsets holding the leggings in shape and over the shoes of a wearer, and fastening means at the overlying edge of the legging comprising a bar having a hook at the top for engaging in the perforations of the plate and attached to the body of the legging at a distance from the end of the bar, the body of the legging being cut away to expose the lower end of the bar providing an unobstructed extremity for engagement in any one of the pockets.
